UNITED STATES PATENT OFFICE

DWIGHT W. COULTAS, OF CRANSTON, RHODE ISLAND

DESIGN FOR A BUCKLE

Application filed September 11, 1930. Serial No. 36,930. Term of patent 3½ years.

To all whom it may concern:

Be it known that I, DWIGHT W. COULTAS, a citizen of the United States of America, residing at Edgewood, city of Cranston, county of Providence, State of Rhode Island, have invented a new, original, and ornamental Design for a Buckle, of which the following is a specification, reference being had to the accompanying drawing, forming a part thereof.

Fig. 1 is a front face view of a buckle showing my new design; and Fig. 2 is a top edge view of the same.

I claim:

The ornamental design for a buckle, substantially as shown.

DWIGHT W. COULTAS.
